UNITED STATES PATENT OFFICE.

JOSEPH ELI MAYO, OF SACRAMENTO, CALIFORNIA, ASSIGNOR OF ONE-HALF TO GEORGE COMBS BASSETT, OF SACRAMENTO, CALIFORNIA.

MACHINE FOR THE MECHANICAL APPLICATION OF PAINTS AND OTHER LIQUIDS.

1,336,041.

Specification of Letters Patent.

Patented Apr. 6, 1920.

Application filed July 25, 1918. Serial No. 246,680.

To all whom it may concern:

Be it known that I, JOSEPH ELI MAYO, a citizen of the United States, residing at Sacramento, in the county of Sacramento and State of California, have invented certain new and useful Improvements in Machines for the Mechanical Application of Paints and other Liquids, of which the following is a specification.

This invention relates to that class of apparatus in which paint or other fluid is applied and distributed by mechanical means. The object of the invention is the applying of paint mechanically by means of a revolving brush. The paint is applied to the periphery of a revolving brush when the brush has been compressed. The object is to provide in a machine of this kind a novel construction and arrangement of parts to be hereinafter described and claimed, whereby a strong, durable and efficient machine is produced.

In order that the invention may be better understood, reference is made to the accompanying drawings, which form a part of this specification, in which:

Figure 1 is a perspective view of the complete machine; Fig. 2 is a top assembly plan view with the paint box (1) removed; Fig. 3 is a front assembly end view with the paint box (1) removed; Fig. 4 is a detail of the brush spindle and sprocket; Fig. 5 is an end view of brush spindle and sprocket; Fig. 6 is the brush clutch yoke; Fig. 7 is a side view of the circular brush; Fig. 8 is an end view of circular brush; Fig. 9 is a side view of feed box chamber and compressing die; Fig. 10 is an end view of feed box and compressing die; Fig. 11 is a section through feed box chamber; Fig. 12 is a side view of adjustable guides; and Fig. 13 is an end view of adjustable guides.

Referring specifically to the drawings, the paint tank (1) is supported on the framing (2) which also serves to brace the machine and the handles (3). The paint or fluid contained in tank (1) is fed through the feeding tube (4), being admitted to feed box chamber (6) See Figs. 1, 9, 10 and 11 through the hollow stem feed valve (5) which allows a free and unobstructed flow. The feed valve (5) is under the direct control of operator by means of lever handle (8) connected to rod (7), and links 7' and

7'', the valve being normally held in closed 55 position by action of spring (9). The paint being admitted through opening (27) to feed chamber (6) flows through opening (10) and is uniformly distributed through the brush (11). 60

The brush (11) is driven by sprocket (12) and chain (13), which receives power and motion from sprocket (38) attached to wheel (14). The lever handle (16) actuates the hinged toggle (17) connected to clutch yoke (18) and operating clutch dogs (19) which pass through holes in the hub (29) of brush (11) and which engage with lugs (31) which are secured to axle (20) the clutch dogs (19) being normally kept from engaging the lugs 70 (31) by action of spring (21).

Spacing plate (22) regulates and restricts the width of surface covered by brush (11), and is attached to brush guide frame (23). The front and rear separator rods (43) and 75 (44) act as spacer and support for the brush guide frame (23), whose lugs (24) and (45) support short rods (25) the lower ends of which pass loosely through lugs (45) and support lower, movable part of brush guide frame (23). Attached in front of the lower part of the brush guide frame (23) is a shoe (26). The springs (46) hold the shoe (26) and spacing plate (22) against the surface over which the machine may be moving and take up unevennesses of surface. The front roller (41) supports the front end of the machine and regulates a maximum compression of the bristles of brush (11) when in contact with surface to be painted, 80 85 the bracket (42) being adjustable and secured to main frame (40) which supports the movable parts. 90

The feed box adjusting screws (33) are attached to feed box (15) and pass through 95 holes in frame when feed box (15) is fitted in place over brush (11). Top adjuster rod (34) attached hinged to extended sides of feed box (15) permits further adjustment of feed box (15). The cover (32) of feed box 100 chamber (6) is packed with a composition washer to prevent leakage of paint, and is separate from feed box (15) to facilitate cleaning. The spindles (28) are threaded in part of their length to corresponding 105 threads within axle (20) for the purpose of permitting brush (11) to be removed for cleaning, the spindles being unscrewed al-

low brush (11) and axle (20) to drop out of frame (40).

It will be noted that as the ends of the bristles of brush (11) come in contact with face and sides of feed box (15) as shown by the dotted lines, Fig. 11, the brush is gradually compressed due to the die being narrower than brush, and the compressing face of the feed box, Fig. 10, decreasing in distance to the center of the hub of the brush, so that the bristles of the brush are bent backward and the maximum compression occurs at the opening (10) through which the brush receives its charge of paint from the feed chamber (6). The brush is gradually expanded to its normal shape and size before leaving the feed box, the entire operation of the combination of the brush (11) and the feed box (15) being similar to the taking up of paint with a brush by hand and distributing it properly within the brush preparatory to painting.

The brush is geared in such a manner as to revolve at increased speed so that bristles flow evenly over surface to be painted with a strong brushing action. The brush (11) can be disengaged from shaft (20) by releasing the clutch, so that the operation of the brush is under the direct control of the operator, as well as the supply of paint to the feed chamber.

The structure herein described is a hand-power machine with a relatively narrow brush, but the invention includes the use of other motive power and large brushes, singly or in combination, with corresponding modifications of the details of the machine. Various other changes and modifications of the structural details may be made without a departure from the scope and spirit of the invention, as well as other fluids than paint may be used with benefit.

Having described my invention and what I claim to be new and useful, I desire to protect by United States Letters Patent:

1. A liquid coating applying machine comprising a suitable frame, a rotatable circular brush, a spindle upon which said brush is mounted upon said frame, driving means for said brush, a clutch for connecting said brush and driving means, and means for operating said clutch.

2. A liquid coating applying machine comprising a suitable frame, wheels carrying said frame, a rotatable circular brush, a spindle upon which said brush is mounted upon said frame, a driving connection between the wheels of said frame and said brush, a clutch in said driving connection, and means for operating said clutch.

3. A liquid coating applying machine comprising a suitable frame, wheels carrying said frame, a rotatable brush, a spindle upon which said brush is mounted upon said frame, a driving connection between

the wheels of said frame and said brush arranged to gear said brush for higher speed than said wheels, a clutch in said driving connection, and means for operating said clutch.

70

4. A liquid coating applying machine comprising a suitable frame, a rotatable circular brush mounted thereon, means for rotating said brush, a feed chamber adjacent said brush and provided with one or more feed openings for supplying liquid to said brush, and a guide coöperating with said feed chamber for compressing the bristles of said brush.

5. A liquid coating applying machine comprising a suitable frame, a rotatable circular brush mounted thereon, means for rotating said brush, a feed chamber adjacent said brush and provided with one or more feed openings for supplying liquid to said brush, a guide coöperating with said feed chamber and arranged to compress the bristles of the brush at and approaching said feed opening or openings.

6. A liquid coating applying machine comprising a suitable frame, a rotatable circular brush mounted thereon, means for rotating said brush, a feed chamber adjacent said brush and provided with one or more feed openings for supplying liquid to said brush, and a guide coöperating with said feed chamber for compressing and flexing the bristles of said brush at said opening or openings.

7. A liquid coating applying machine comprising a suitable frame, a rotatable circular brush mounted thereon, means for rotating said brush, a feed chamber adjacent said brush and provided with one or more feed openings for supplying liquid to said brush, and means adjacent said feed opening or openings for flexing the bristles and thereby exposing a portion of their length to the liquid at said opening or openings.

8. A liquid coating applying machine comprising a suitable frame, a rotatable circular brush mounted thereon, means for rotating said brush, a feed chamber adjacent said brush and provided with one or more feed openings for supplying liquid to said brush, and a guide coöperating with said feed chamber having a surface for contact with said bristles curved on a radius greater than the radius of curvature of the circular brush.

110

9. A liquid coating applying machine comprising a suitable frame, a rotatable circular brush mounted thereon, means for rotating said brush, a feed chamber adjacent said brush and provided with one or more feed openings for supplying liquid to said brush, and a guide coöperating with said feed chamber and formed to compress and flex the bristles of said brush as they approach said feed opening or openings and

115

120

125

130

to gradually cause said bristles to straighten as they approach the surface coating position.

10. A liquid coating applying machine comprising a suitable frame, wheels for carrying said frame over a surface to be coated, a rotatable brush mounted on said frame, means for rotating said brush, means for supplying liquid to said brush, and a combined 10 guide and spacer for the brush slidable over and upon said surface.

11. A liquid coating applying machine comprising a suitable frame, wheels for carrying said frame over a surface to be coated, 15 a rotatable brush mounted on said frame, means for rotating said brush, means for supplying liquid to said brush, and a combined guide and spacer for the brush having a plate at each side of the brush spring 20 mounted upon said frame and slidable over said surface.

12. A liquid coating applying machine comprising a rotatable cylindrical brush, means for rotating said brush over a surface 25 to be coated, and a guide plate yieldably mounted at each side of said brush for sliding engagement with said surface and to contact with the brush to hold the latter true and regulate the width of stripe.

30 13. A liquid coating applying machine comprising a rotatable cylindrical brush, means for rotating said brush over a surface

to be coated, and a guide plate yieldably mounted at each side of said brush and adjustable axially thereof for sliding engagement with said surface and to contact with the brush to hold the latter true and regulate the width of stripe. 35

14. A liquid coating applying machine comprising a suitable frame, a rotatable 40 brush mounted on said frame, means for supplying liquid to said brush, two rods extending across said frame, one in front and one in rear of said brush, and a guide plate 45 at each side of said brush, each said guide plate being adjustably secured to said rods.

15. A liquid coating applying machine comprising a suitable frame, a rotatable brush mounted on said frame, means for supplying liquid to said brush, two rods extending across said frame, one in front and one in rear of said brush, a guide frame at 50 each side of said brush, each said frame being secured to said rods for adjustment toward and from said brush, and a guide plate 55 for each end of the brush bristles mounted on each said guide frame for yielding contact with the surface to be coated.

In testimony whereof I affix my signature in presence of two witnesses.

JOSEPH ELI MAYO.
